UNITED STATES PATENT OFFICE.

JOSEPH U. BLOSE, OF GRANT, PENNSYLVANIA.

DESIGN FOR A SLEIGH-SHAFT.

SPECIFICATION forming part of Design No. 15,527, dated November 11, 1884.

Application filed August 11, 1884. Term of patent 14 years.

To all whom it may concern:

Be it known that I, JOSEPH U. BLOSE, of Grant, county of Indiana, and State of Pennsylvania, have invented and produced a new and original Design for Sleigh-Shafts, of which the following is a full, clear, and exact description.

My design for sleigh shafts or thills consists in a novel configuration of the rear portion of said shafts or thills, more especially the one of them, as hereinafter described, and shown in the accompanying drawings.

Reference is to be had to the accompanying drawings, forming part of this specification, in which similar letters of reference indicate corresponding parts in all the figures.

Figure 1 represents a view in perspective of a pair of sleigh-shafts embodying my design; Fig. 2, a top view of the same, and Fig. 3 a side view thereof.

A indicates the one and B the other thill of a pair of sleigh shafts or thills. The rear portion of the shaft or thill A, extending from a point, a, to a point, b, is made to gracefully curve backward, downward, and inward, its backward and inward curvature being more clearly shown in Fig. 2, and its combined backward and downward curvature in Fig. 3. From the point b to the extreme limits of said

rear portion of the shaft A the configuration 30 of such inward extension of said shaft is straight, and at right angles to a longitudinal central vertical plane passing between the two shafts A B. This straight inner shaped portion between b and c of the shaft A is relieved or broken by a graceful backward and downward curvature of the rear portion, e, of the shaft B. The rear portions of the two shafts thus present a novel and ornamental appearance, and more particularly so said 40 portion of the shaft A by reason of its triple curvature and straight configuration combined, as shown and described.

I claim—

The design for sleigh-shafts, which consists 45 in the shaft A, bent downward and inward between the points a b, and extending in a straight line from the point b to the terminating-point c, the shaft B parallel with shaft A, and bent at e to correspond with the downward bend in said shaft A, the downward-bent end e joining the shaft A between the points b c, as shown.

JOSEPH U. BLOSE.
